UNITED STATES PATENT OFFICE.

SAMUEL T. BROCK, OF MOUNT VERNON, OHIO.

PUTTYLESS WINDOW SASH AND PANE HOLDER.

1,110,530.

Specification of Letters Patent. Patented Sept. 15, 1914.

Application filed December 4, 1912. Serial No. 734,942.

To all whom it may concern:

Be it known that I, SAMUEL T. BROCK, a citizen of the United States, residing at Mount Vernon, in the county of Knox and State of Ohio, have invented certain new and useful Improvements in Puttyless Window Sashes and Pane Holders, of which the following is a specification.

This invention relates to certain new and useful improvements in window sashes and means for securing glass therein, and has for its primary object, the provision of a puttyless window sash and pane holder, which shall be of extremely simple construction, cheap to manufacture, and which may be easily and quickly assembled.

Another object of the invention is to provide a sash and pane holder which is so constructed as to permit a free circulation of air around the window pane so as to prevent condensation forming thereon.

The invention also aims to provide means whereby water may be drained from the pane and sash; whereby a circulation of air may be maintained around the inner sides of the sash bars so as to prevent them rotting; and whereby a pane of glass may be firmly held in position without the use of putty.

With these and other objects in view, as will become more apparent as the description proceeds, the invention consists in certain novel features of combination, construction, and arrangement of parts, as will be hereinafter more fully described and claimed.

For a complete understanding of my invention, reference is to be had to the following description, and accompanying drawings, in which,

Figure 1 is an interior side elevation of a window frame embodying my invention, the frame being partly broken away, Fig. 2 is a vertical sectional view, Figs. 3 and 4 are transverse sectional views taken upon the plane of line 3—3 and 4—4, respectively, of Fig. 1, Fig. 5 is a fragmentary elevation, partly in section, showing the upper end of the top sash, Fig. 6 is a fragmentary view in elevation, of the upper portion of the lower sash, and, Fig. 7 is a view of the frame formed by pane holding tubes, said tubes being slightly modified.

Referring in detail to the drawings by numerals, 1 designates a window frame, having secured thereto the guide strips 2,

and 3 designates the sill. The upper sash, generally designated 4, comprises the side bars 5, top bar 6, and bottom bar 7. The ends of these bars are connected in any desired or usual manner to form the sash frame and are provided along their inner faces with grooves 8, essentially semi-circular in cross-section. The longitudinal channel 9 is formed in the bottom of each of the grooves 8 and the channel which is formed in the top bar 6 communicates with an angular opening 10, which opens upon the outer face of said sash bar. Preferably metal guard plates 11 are secured at their upper ends to the bar 6 and extend downwardly over the outer ends of the openings 10 in spaced relationship thereto, whereby a free passage of air is permitted through said openings but rain water is excluded therefrom. The lower sash bar 7 is formed with a plurality of slots 12, opening at their lower ends upon the bottom of said bar and communicating at their upper ends with the channel 9 formed therein.

The lower sash 13 comprising the side bars 14, top bar 15, and bottom bar 16, is formed essentially similar to the upper sash 4 and is provided with the grooves 17 and channels 18. The side bars 14 are formed with the angular openings 19, which open at their outer ends upon the exterior of the sash and communicate at their inner ends with the grooves 18 formed in said side bars. The bottom bar 16 is formed with the slots or passages 20, which communicate at their inner ends with the channel 18 formed in said bar and open at their outer ends upon the bottom face of said bar, which is provided with the transverse grooves 21.

The panes 22 of the sashes are held within their respective grooves 8 and 17 by means of the tubes 23. These tubes are formed with a longitudinal slot to receive the edges of the window panes and have the metal adjacent to the edges of said slots preferably turned inwardly, as indicated at 24, to present a good clamping surface to the window panes. The ends of the tubes 23 are mitered, as indicated at 25, so as to form good joints. These tubes are fitted within the grooves 8 and 17 and project inwardly a slight distance beyond the walls of the same, and are slotted at spaced intervals along their inner edges, and the alternate portions between 110 said slits bent outwardly, as indicated at 25. Certain of the tubes are formed with the

openings 26, which communicate with the grooves 8 and 17.

To assemble my improved sash and pane fastener, the holding tubes 23 are first 5 slipped onto the edges of the pane and then said pane and tubes are positioned within the sash, one of the sash bars being removed for this purpose. In operation, air will flow into the channels 9 through the openings 10 and 19 and the slots 12 and 20. The cool air 10 will enter near the tops of the sashes and circulate entirely around the same through the continuous channels 9 and 18. The openings 26 in the tubes 23 permit air to enter 15 these tubes and circulate through the same, said air passing out through the passages formed by the outwardly bent portions 25. Any water which gathers upon the upper pane 22, will run into the tube 23 upon the 20 sash bar 7, at the openings 26 in said tube, into the channel 9, and out through the slots 12. Water gathered upon the lower pane 22 will be similarly drawn off through the 25 openings 26, passages 20, and notches 21. It will thus be seen that I have provided an improved puttyless window sash and pane holding tubes, which coöperate to securely fasten a pane in position and at the same time permit a free circulation of air about

the pane and along the inner sides of the sash bars. The construction, as hereinbefore 30 stated, tends to prevent condensation forming upon the window panes and provides for the draining off of the same should it form.

It is to be understood that while I have 35 shown and described the preferred embodiment of my invention, I do not wish to be limited to this exact construction, combination and arrangement of parts, but may make such changes as will fall within the 40 spirit and scope of the invention.

Having thus described my invention, what I claim is:—

A window pane receiving tube, having a 45 slot formed along one side thereof, the edges of said slot being bent inwardly to provide gripping flanges, said edges being slotted at intervals and the offset portions between said slits being bent outwardly, whereby air 50 may circulate through said tube, and means for holding the tube in position.

In testimony whereof I affix my signature in presence of two witnesses.

SAMUEL T. BROCK.
